ROBERT E. McGOWAN AND FREDRICK W. McCORRY, OF COWLEY, WYOMING.

COMBINATION RULE, SQUARE, AND LEVEL.

Application filed January 10, 1922. Serial No. 528,279.

To all whom it may concern:

Be it known that we, ROBERT E. McGOWAN and FREDRICK W. McCORRY, citizens of the United States, and residents of 5 Cowley, in the county of Big Horn and State of Wyoming, have invented new and Improved Combination Rules, Squares, and Levels, of which the following is a description.

10 The general object of our invention is to provide a sectional tool having novel means whereby to adapt it to be readily converted into a rule or a square at will, one of the sections constituting a level.

15 The nature of the invention, its distinctive features and advantages will clearly appear as the description proceeds.

Reference is to be had to the accompanying drawings forming a part of this specification, it being understood that the drawings are merely illustrative of one example of the invention.

Figure 1 is a side elevation of one of the sections;

25 Figure 2 is a cross section on the line 2—2, Figure 1;

Figure 3 is an end view of one of the sections;

30 Figure 4 is an edge view of said section at one end;

Figure 5 is an elevation of a screw plug to be hereinafter referred to;

Figure 6 is a partly sectional side elevation of an end of the second section;

35 Figure 7 is a cross section on the line 7—7, Figure 6;

Figure 8 is a sectional side view of the adjacent ends of the sections when connected in the form of a square.

40 In carrying out our invention in accordance with the illustrated example, two elongated sections 10, 10^a are provided having scales thereon, one of the sections being formed with a frame 11 to receive level glasses 12 and guard glasses 13 therefor.

45 At one end of a section, as 10, we provide a transverse casing 14 and provide a similar casing 15 longitudinally disposed at the other end of the section, the two casings thus being at right angles. Within each casing 14, and 15, is a socket 16 having parallel recesses or undercuts 17 diametrically opposite. An internally threaded socket 18 is provided on the other section 10^a at an end 50 thereof to which is secured the threaded end

19 of a connecting element 20 which projects beyond the socket 18 and is provided with lateral lugs 21 in pairs diametrically opposite to be inserted in a socket 16 and given a partial turn to enter the lugs in the under- 60 cuts 17. The arrangement is such that the sections may be disposed in longitudinal alinement with the connecting element 20 in the socket 16 to constitute the device a rule or said connecting element may be inserted 65 in the other socket 16 as shown in Figure 8, thereby disposing the sections 10, 10^a at right angles to each other to constitute a square.

In order to prevent play of the connected 70 sections we provide screws 22 adapted to be accommodated in holes 23 in the respective sections, the screws passing through holes in one section and being in threaded engagement with the holes in the other section. 75 Thus, the sections 10, 10^a may be separated for assembling the same in knocked down form in which case the connecting element 20 may be unscrewed from the outer end of the socket 18 and inserted in the inner end of 80 said socket as indicated by dotted lines in Figure 6. In the latter position of the connecting element 20 the socket 18 may be closed by a screw plug 24. The sockets 16 may be fastened in the casing 14, 15 by a set 85 screw 16^a indicated as seen in Figure 8.

We would state in conclusion that while the illustrated example constitutes a practical embodiment of our invention, we do not limit ourselves strictly to the exact details 90 herein illustrated, since manifestly the same can be considerably varied without departure from the spirit of the invention as defined in the appended claims.

Having thus described our invention, we 95 claim: —

1. A device of the class described comprising separate sections, one section having sockets at right angles to each other and adjacent to the respective ends, the other section having a connecting element adapted to either of said sockets to dispose the sections in alinement with each other to constitute a rule, or at right angles to each other to constitute a square, together with screw 100 means on one section to securely clamp the sections in either position.

2. A device of the class described comprising separate sections, one section having sockets at right angles to each other and ad- 110

5 jacent to the respective ends, the other section having a connecting element adapted to either of said sockets to dispose the sections in alinement with each other to constitute a rule, or at right angles to each other to constitute a square, one of the sections presenting a 10 socket at each end, one at right angles to the other, and a fastening screws for securely connecting the sections in either position, the respective sections having screw holes adjacent to the sockets to receive said screws.

15 3. A device of the class described including sections adapted to be disposed in longitudinal alinement to constitute a rule or at right angles to each other to constitute a square, one of the sections presenting a 20 socket at each end, one at right angles to the other, and a fastening element to connect the sections, said element having means to secure it to one section and presenting lateral lugs, the sockets of the other section having recesses corresponding with said lugs and adapted to receive the latter by a partial turning of the one section relatively to the other.

25 4. A device of the class described including sections adapted to be disposed in longitudinal

30 alinement to constitute a rule or at right angles to each other to constitute a square, one of the sections presenting a 35 socket at each end, one at right angles to the other, and a fastening element to connect the sections, said element having means to detachably secure it to one section and presenting lateral lugs, the sockets of the other section having recesses corresponding with said lugs and adapted to receive the latter by a partial turning of the one section relatively to the other.

35 5. A device of the class described including sections adapted to be disposed in longitudinal alinement to constitute a rule, or at right angles to each other to constitute a square, one of the sections presenting a 40 socket at each end, one at right angles to the other, and a fastener element for the sections, carried by the other section, said fastener element having detachable engagement with the last-mentioned socket, and having a series of lug members to engage in either of the sockets of the other section.
